SERVING TRAY

William Bruce Prentice and Jeannette L. Prentice,
Great Falls, Mont.

Application October 18, 1954, Serial No. 32,701

Term of patent 3½ years

(Cl. D44—19)

Fig. 1

Fig. 2

Fig. 3

Fig. 4

Fig. 1 is a perspective view of a serving tray, showing our new design;

Fig. 2 is a top plan view;

Fig. 3 is a bottom plan view;

Fig. 4 is a side elevational view from the left side of Fig. 1;

Fig. 5 is a view in perspective taken from the side opposite to Fig. 1; and

Fig. 6 is a bottom view in perspective showing the serving tray of this invention and particularly the rib structure incorporated therein.

We claim:

The ornamental design for a serving tray, as shown and described.
